UNITED STATES PATENT OFFICE.

HARRY C. KETTELSON, OF MILWAUKEE, WISCONSIN.

ROOFING-CLEAT.

1,225,972.

Specification of Letters Patent.

Patented May 15, 1917.

Application filed August 19, 1916. Serial No. 115,784.

To all whom it may concern:

Be it known that I, HARRY C. KETTELSON, a citizen of the United States, and resident of Milwaukee, in the county of Milwaukee

5 and State of Wisconsin, have invented certain new and useful Improvements in Roofing-Cleats; and I do hereby declare that the following is a full, clear, and exact description thereof.

10 The present invention relates to new and useful improvements in metallic cleats particularly adapted for securing roofing sheets to the roof board of buildings, and for use in other connections wherein the cleats would be exposed to the weather and wherein it is desired to procure a binding action along the entire lengths of the cleats.

It is in general the object of the present invention to provide a cleat which may be 20 manufactured at a minimum cost consistent with a desired degree of durability and efficiency and it is more particularly an object to provide a roofing cleat formed of wire wherein a considerable economy of 25 material is effected both by reducing the amount of material essential in the finished cleat, and by eliminating wastage of stock in forming the cleat.

It is further an object to provide a wire 30 cleat structure wherein the advantage of a complete seal for the nail is procured to prevent excessive rusting of the nails.

It is still further an object to provide a wire cleat wherein the stretches of wire between the nail receiving portions extend below said portions adapted to positively bite into the roofing material upon applying the cleat.

With the above and other objects and advantages in view the invention resides more particularly in the novel combination, arrangement and formation of parts more particularly hereinafter described and pointed out in the appended claims.

45 In the drawings:

Figure 1 is a side elevation of a portion of a section of wire cleat constructed in accordance with the present invention, and associated with a lapped pair of roofing sheets, which are shown in section.

Fig. 2 is a top plan view of one of the nail receiving portions of the cleat section, with the head of the nail broken away.

Fig. 3 is a bottom plan view of the nail receiving portion.

55

Fig. 4 is a plan view of a modified form or wire cleat.

Fig. 5 is a vertical sectional view through one of the nail receiving portions of this modified form of cleat with a nail disposed 60 therein, this view being indicated by the line 5-5 of Fig. 4.

Referring now more particularly to Figs. 1 to 3 of the drawings, 5 designates the body of the cleat which is formed of wire 65 of any desired length and which has spaced flattened upwardly offset portions 6 centrally apertured to receive nails 7 which are preferably associated with the portions 6 during the manufacture of the cleat and 70 which comprises wire lengths inserted through the portions and swaged to provide the heads 8, and to procure a water tight seam between the heads and shanks, and said nail receiving portions. These nail 75 receiving portions are preferably formed by first flattening the wire and then spreading the flattened portions by the formation of the apertures therein, thus procuring a maximum amount of material in said portions. The flattened bottoms of these portions form an annular seal about the shanks of the nails which effectively prevent possible leakage of water between the portions and the roof, and said flattened bottoms also 80 engage the roof to prevent any excessive movement of the cleat into the roofing which might produce possible damage thereto upon applying the cleat.

Those portions of the wire between the 90 nail receiving portions project therebelow and thus upon application of the cleat are adapted to press into the roofing to provide a proper gripping action, it being noted that in view of the relatively large diameter of the wire and in view of its cylindrical shape, there is but slight tendency to cut the sheets of roofing, although it may in certain instances be found desirable to utilize wire of other than cylindrical shape, and wire of 95 rectangular cross section may be employed.

In Figs. 4 and 5 a modified form of cleat is shown which comprises the length of wire 5 bent at spaced intervals to form nail receiving loops 9 which project alternately 100 at opposite sides of the body of the cleat

105

2
and which have their mouths closed to prevent passage of water therethrough and the apertures defined by these loops are circular to receive the head portions of nails 10. 5 These nail head portions are secured in the loops by swaging them, to laterally expand the metal above and below the loops, whereby at the same time a water proof joint is procured to prevent possible rusting at the shanks of the nails. The lower swaged nail head portions form flat surfaces in conjunction with the bottoms of the nail receiving portions and these flat surfaces perform the same functions of annular water seals 15 for the nails and of stops limiting movement of the cleat into the roofing as brought out in conjunction with the nail receiving portion 6 of the preferred form of cleat heretofore described. The formation of these flat surfaces in the present type of cleat would be also effected in part by the flattening of the bottoms of the loop portions coincident to the swaging operation 20 on the heads of the nails. 25 By the foregoing structure, a cleat is provided wherein wastage of material incidental to manufacture is entirely eliminated, and further wherein an economy of material procured inasmuch as all of the metal is disposed immediately at the single binding edge of the cleat. Also the present cleat presents no cavities or channels whereby is entirely avoided the possible disadvantage 30

of rusting and of expansion by freezing due to accumulation of water in the cleat. 35

I claim:

1. A roofing cleat comprising a strip of wire having spaced portions flattened whereby the portions of wire therebetween extend below said spaced portions to grippingly engage a roof and said spaced flattened portions being provided with nail receiving apertures. 40

2. A roofing cleat comprising a strip of wire having spaced portions flattened whereby the portions of wire therebetween extend below said spaced portions to grippingly engage a roof, said spaced flattened portions being provided with nail receiving apertures, and nails disposed in said apertures 45 and having their adjacent portions swaged to secure the nails in the apertures and to provide water tight joints between the nails and the flattened portions. 50

3. A roofing cleat comprising a strip of wire having spaced portions flattened and upwardly offset whereby the portions of wire disposed therebetween extend below said spaced portions to grippingly engage in a roof and said flattened portions being 55 provided with nail receiving apertures. 60

In testimony that I claim the foregoing I have hereunto set my hand at Milwaukee, in the county of Milwaukee and State of Wisconsin.

HARRY C. KETTELSON.
